ELECTRICAL TRANSMISSION SYSTEM

Julius Gourgues Aceves, New York, N. Y., assignor to Revelation Patents Holding Company, New York, N. Y., a corporation of Delaware

Application April 28, 1931, Serial No. 533,396
Renewed February 3, 1934

31 Claims. (Cl. 179—171)

This invention relates to transmission systems, and with particularity to systems employing electron discharge devices as repeaters or amplifiers.

5 An object of the invention is to provide a repeater system which is capable of transmitting current variations of larger amplitude without appreciable distortion.

Another object of the invention is to provide 10 an improved method of coupling a series of electron discharge devices in tandem without employing an external grid bias on any of the stages.

Another object of the invention is to provide 15 a repeater employing a plurality of electron discharge devices in cascade wherein one of said devices is capable of being operated with a positive grid bias and is provided with means for limiting the normal plate current through said device.

20 Another object of the invention is to provide a repeater or amplifier system employing a stage having a positive grid bias together with means for enabling the output stage to handle large powers without distortion.

25 Another feature of the invention relates to an amplifying system employing a plurality of electron discharge devices in cascade wherein the grid of one tube is directly connected to the cathode of a preceding tube and the grid of said preceding tube is connected to the cathode of the succeeding tube together with means for limiting the normal plate current of the said succeeding tube.

30 Another feature of the invention relates to an amplifier system employing a plurality of cascaded electron discharge devices wherein the grid of one device is connected directly to the cathode of a preceding device, together with 35 means for maintaining said connected grid and cathode at substantially ground potential without substantially affecting the amplifying powers of the system.

Another feature of the invention relates to an 40 amplifying stage employing an electron discharge device, the input circuit of said device being provided with another electron discharge device which compensates for the grid loss of the first mentioned amplifier device, together with means 45 for limiting the normal plate current of the said device to a minimum value.

Another feature relates to the novel organization 50 and arrangement of elements and circuits which go to make up an efficient amplifier system 55 capable of operating without distortion, and

without employing so-called negative grid bias.

Other features and advantages not specifically enumerated will be apparent after a consideration of the following detail descriptions and the appended claims.

5 Referring to the drawings:

Fig. 1 represents an amplifier circuit to which the invention is especially well adapted. This circuit is of the type disclosed and claimed in application Serial No. 394,172, filed September 21, 1929, patented May 22, 1934, No. 1,959,540;

Fig. 2 shows the circuit of Fig. 1 modified in accordance with the invention to maintain the normal plate current of the second tube at a low value;

15 Fig. 3 shows substantially the same circuit as Fig. 2, and in addition shows in detail the method of energizing the filament cathode from a direct current source;

Fig. 4 shows the system of Fig. 2 with means 20 for energizing the cathodes from an alternating current source;

Fig. 5 is a typical schematic circuit diagram 25 showing the invention applied to a sound reproducing system.

Referring more particularly to Fig. 1, the numerals 1 and 2 represent schematically audions, or electron discharge devices of the type employing an electron emitting cathode, a control grid and a plate or anode. The cathode 3 of the 30 device 1 is directly connected by a conductor 4 to the control grid 5 of the device 2, and similarly the cathode 6 of the device 2 is connected by a conductor 7 through an input device or coil 8 to the control grid 9 of the device 1. The operating potential for the anode 10 and the anode 11 is derived in accordance with usual practice, from a direct current source 12, the positive end of which is connected to the said anodes and the negative end of which is grounded. In addition, there is a connection 13 between the negative end of the source 12 and the cathode 6 in accordance with standard practice. In other words, the output circuit of the device 2 comprises the anode 11, the primary winding 14 of 35 an output transformer source 12 and cathode 6. The input circuit for said device 2 comprises grid 5, conductor 4, cathode 3, the electron stream between members 3 and 10, conductor 15, source 12, cathode 6. In other words the 40 input circuit for the device 2 includes the electron stream between the cathode 3 and the anode 10. This electron stream is adapted to be varied in accordance with well known principles by the control grid 9, which has its potential varied 45

5 by the input element 8, as described in said application, Serial No. 394,172. The variations in potential of the grid 9 are repeated as corresponding charges on the grid 5. One explanation for this repeating action may be that as the grid 9 varies, the number of electrons leaving the filament for the plate 10, correspondingly vary, and therefore the charge or potential condition of the cathode 3 will follow the potential 10 changes in the grid 9. Similarly the potentials of grid 5 corresponding to the potentials of grid 9 vary the electron stream between members 6 and 11, and thus control the current in the output circuit of the device 2.

15 As described in said application, the grid 5 requires no external negative bias to enable the said device 2 to amplify the impressed potentials with maximum faithfulness. In other words, even though the grid 5 should swing positively 20 there would be no disproportion in the plate current as compared with the plate current produced when the said grid 5 should swing an equal amount negatively. As a matter of fact, with the particular circuit arrangement shown 25 in Fig. 1, the grid 5 is at all times essentially positive with respect to the associated cathode 6, regardless of the potential variations on the grid 9.

Under these conditions therefore, there is a 30 relatively high normal plate current flowing through the output circuit of the device 2. In other words, the main average potential of the grid 5 with respect to the cathode 6 is relatively high and positive. The average normal plate 35 current corresponding to this average positive potential of the grid 5 performs no useful work in transmitting the signals or potential variations desired. Furthermore, this high normal plate current tends to heat the elements of the 40 tube. Inasmuch as there is a practical limit to the power output of any given tube, it will be at once apparent that this normal plate current very seriously limits the useful power in the signal variations that can be transmitted.

45 There is shown in Fig. 2, one manner of limiting and materially reducing the normal plate current of the device 2 without materially affecting the amplifying powers of the system. In Fig. 2 the corresponding elements to those of Fig. 1 are designated by the same numerals. From an inspection of Fig. 2 it will be noticed 50 that the only difference is that the connection 4 between the cathode 3 and the grid 5 is connected to ground through a reactance coil 16. If the coil 16 is of an extremely low ohmic 55 resistance, then the grid 5 may be considered to be practically at ground potential when no alternating E. M. F.'s are impressed on the grid 9. In other words, the normal current from source 60 12 divides, one portion passing from the positive pole of source 12, conductor 15, anode 10, cathode 3, high reactance 16, to the negative pole of the source 12. At the point 17 the current divides and part flows to the grid 5, cathode 6, and returning to the negative end of the source 12. 65 However, since the ohmic resistance of the reactance 16 is vanishingly small, the potential drop thereacross will be substantially negligible and the grid 5 will remain at substantially 70 ground potential.

75 When an alternating E. M. F. is impressed upon the grid 9 there is produced a corresponding change in the electron stream between elements 3 and 10. Preferably the inductance of coil 16 is so large that for the lowest impressed

frequency its reactive impedance is greater than the plate-cathode impedance of the device 1. Under these conditions, therefore the reactive voltage developed by the passage of the signal variations through the coil 16 will be applied directly between the grid 5 and the cathode 6, and will produce corresponding changes in the output circuit of the device 2.

10 Although Fig. 2 of the drawings shows the grid 5 at substantially ground potential under normal conditions, it will be understood that the normal potential of the grid 5 may be at any value determined by the desired normal current in the output circuit of device 2. Thus a suitable source of steady potential may be inserted 15 between the coil 16 and the ground, although satisfactory operation is secured without such external potential, and the circuit of Fig. 2 may be arranged to provide any frequency-gain characteristic required for the system as a whole. 20 For example, the coil 16 may be provided with any other form of reactance or resistance in shunt and/or in series therewith in order to obtain different voltage drops for the various frequencies, or if desired, these additional reactances may be used for the purpose of controlling 25 the phase angles between the various impressed frequencies.

30 For example, a resistance connected in parallel with the coil 16 provides a simple and efficient method of obtaining uniform gain at all audio frequencies. It will be understood, of course, that the circuit of Fig. 2 may be used for the transmission of any range of frequencies, for example, if the system is designed to transmit 35 audio frequencies then the coil 16 will be designed to have an extremely low ohmic resistance, but a high reactance to the audio frequencies. Similarly, if the system is to be used for the transmission of radio frequencies, the coil 40 16 will likewise have very low resistance, but will have high reactance to the radio frequencies.

45 While the circuit of Fig. 1 shows the output load represented schematically by a load resistance, it will be understood that this is purely 45 illustrative and that instead of a resistance load, any other type of load may be employed, and this load circuit may be coupled to the tube 2 in any other manner than by transformer coupling as shown.

50 While Fig. 2 does not show the particular circuits for rendering the cathodes 3 and 6 emissive, it will be understood that any suitable filament heating circuit may be employed.

55 For example, Fig. 3 shows a circuit arrangement whereby the same current used for the anode supply may be used for heating the filaments. The current supply conductors 18 are adapted to be connected to a suitable source of direct current and resistances 19 and 20 may be 60 connected in series with the cathodes 3 and 6 to provide the proper value of current for heating these filaments. In addition it may be found desirable to employ a pair of high reactance coils 21 and 22 in circuit with both legs of the 65 filament 3, in place of a single reactance such as schematically shown in Fig. 2. The reactance coils 21 and 22 may be on separate cores, or if desired, they may be wound on a single core provided that the two windings 21 and 22 are connected in such a direction that they will aid each other for alternating currents, and oppose each other for direct currents, and preferably, although not necessarily, the same number of turns 70 may be employed on each coil.

With the circuit arrangement of Fig. 3 it is preferred to employ, for the tube 1, an audion which requires low filament current, and has a low amplification factor. For example, one type of tube that has been found successful for this purpose employs a filament current of 0.06 amp. and has an amplification factor of 3.5.

Fig. 4 shows the circuit of Fig. 2 wherein the first audion is of the so-called indirectly heated cathode type, that is to say, instead of the filament 23 being itself an electron emitter, it is used merely to heat another element or sleeve 24, which carries the electron emissive substance. The element 24 is therefore the cathode and functions similarly to the filaments 3 of Figs. 1 to 3. In this case the heater filament 23 and the electron filament 6 are connected in parallel with the secondary winding 25 of a filament supply transformer whose primary winding 26 is connected to a suitable source of alternating current. The direct connection between the cathode 24 and the grid 5 is maintained at substantially ground potential, it being connected to ground thru the high reactance, low resistance coil 16 as above described. The grid return for the tube 2 is preferably, although not necessarily, effected to the midpoint of the transformer winding 25 in accordance with usual practice. The operation of the circuit of Fig. 4 is substantially the same as that described in connection with Fig. 2, and further description thereof is not believed necessary at this point.

Fig. 5 shows a typical circuit arrangement embodying the invention in a sound reproducing system. In this figure the numeral 27 represents a sound record of any well known type, which by means of the pick-up device 28, is translated into corresponding potential variations. These potential variations are impressed upon the grid 40 cathode circuit of the audion 29, the output circuit of which is coupled, by means of the transformer 30, to the input circuit of the tube 31 which corresponds to the tube 1 of Figs. 1 to 4 inclusive. The amplified variations impressed upon the grid 32 of device 31 are repeated to the grid 33 of the audion device 34 in the manner set forth in application Serial No. 394,172. The grid is likewise connected through the high reactance coil 35 to the conductor 36, which may be at ground or other selected fixed potential for the purpose of limiting or controlling the normal plate current in the device 34, as hereinabove described. The grid 33 therefore responds to the potential drops across the reactance 35, and correspondingly varies the output of the tube 34, which is coupled by a suitable output circuit to the sound reproducing device 37. While the source of potential for the anodes and cathodes of the respective tubes is not shown in Fig. 5, the manner of connecting these sources to the respective electrodes is in accordance with standard practice, and no description thereof is believed necessary.

While Figs. 1 to 5 show the invention embodied in two separate audions having their grids and cathodes directly interconnected, it will be understood that the invention may also be practiced by combining the said audions in a single audion of the type disclosed in Patent No. 2,002,207, May 21, 1935.

While the invention has been disclosed in connection with specific types of electron discharge devices, and associated apparatus, it will be understood that the invention is not limited thereto, but may be practiced with other well known forms of apparatus without departing from the

spirit and scope of the invention. One of the important advantages of applicant's specific circuit arrangements is that the variation in potential of the first grid with respect to its cathode is in phase with the variations in potential of the second grid with respect to its cathode. In other words, as an incoming signal raises the potential of the grid 7 with respect to its cathode 3, there is a corresponding increase in potential applied across the grid 5 and the cathode 6, so that as the grid 9 swings positively with respect to its cathode 3, likewise the grid 5 swings positively with respect to its cathode 6. In this sense, therefore, the variations of grid potentials with respect to the associated cathodes are in phase.

What is claimed is:

1. In a wave transmission system a first electron discharge device, a second electron discharge device, a high-reactance coil connected in shunt to the grid-cathode of the first device and the grid-cathode of the second device, one terminal of said reactance coil being connected to ground for maintaining the grid of the second device at or near ground potential when no signals are being transmitted.

2. In a wave repeating system a series of electron discharge devices with the grid of one device directly connected to the cathode of a preceding device, and reactance means for maintaining the grid of said second device at substantially ground potential when no signals are being repeated.

3. In a transmission system the combination of a first electron discharge device, a second electron discharge device, each device having a grid-cathode input circuit, means common to both said input circuits and connected in series with the grid-cathode of the first device to limit the normal plate current of the second device, and circuit arrangements for allowing said second device to operate with a positive static bias on the grid without causing distortion in the output.

4. In an amplifying system the combination of a first electron discharge device, a second electron discharge device, a high reactance connected in common to the grid-cathode circuits of each of said devices, and circuit arrangements for impressing signal variations on the grid of the first device so that variations in potential between the grid of the first device and the cathode of the second device are in phase with the variations in potential between the grid and cathode of the second device.

5. A combination according to claim 4 in which the high reactance has low ohmic resistance.

6. In an amplifying system the combination of a first electron discharge device, a second electron discharge device, the cathode of said first device being directly connected to the grid of said second device, and the cathode of said second device being connected in a direct current circuit to the grid of said first device, means for limiting the normal anode currents of said second device, and circuit arrangements for impressing signal variations on the grid of the first device so that variations in potential between the grid of the first device and the cathode of the second device are in phase with the variations in potential between the grid and cathode of the second device.

7. The combination according to claim 6 in which the means for limiting the anode current of the second device includes a high reactance between the grid of said second device and the cathode thereof.

8. In an amplifier system a first electron discharge device, a second electron discharge device,

- 5 a source of anode potential for said second device, a connection between the grid of said second device and the positive terminal of said source, said connection including the cathode-anode space of the first device, means for limiting the 10 normal anode current of the second device when no signals are being transmitted, and circuit arrangements for impressing signal variations on the grid of the first device so that variations in potential between said grid and the cathode 15 of the second device are in phase with the variations in potential between the grid and cathode of the second device.
- 16 9. A system according to claim 8 in which the means for limiting the normal anode current includes a low resistance high reactance element connected between the grid of said second device and ground, said ground being at a negative pole of the anode supply.
- 17 10. In an amplifier system the combination of an electron discharge device having an electron emitting cathode, a controlling grid and an anode, a circuit connecting said grid and cathode including an input element, and a low resistance high reactance element connected in series, and another electron discharge device having its grid connected to the one end of said reactance and its cathode connected to the opposite end of said reactance.
- 18 11. An amplifier system according to claim 10 in which one terminal of said high reactance is substantially at ground potential with respect to the signal variations.
- 19 12. In an amplifier system the combination of a first electron discharge device, a second electron discharge device, each of said devices having a cathode, a control grid and an anode, a low resistance high reactance element, the cathode of the first device being connected to one terminal of said reactance and the grid of the first device and the cathode of the second device being connected to the other terminal of said reactance.
- 20 13. A wave repeating system comprising a pair of electric discharge devices each having cathode, anode and control electrodes, a low-resistance high-reactance connected in shunt to the cathode and control electrode of the second device, and a signal input circuit connected in series with said reactance across the cathode and control electrode of the first device.
- 21 14. A wave repeating system according to claim 13 in which one end of said reactance is substantially at ground potential with respect to the signal variations.
- 22 15. A wave repeating system according to claim 13 in which there is a direct metallic connection between the grid of the first device and the cathode of the second device.
- 23 16. A wave repeating system of the type employing a pair of three-electrode electric discharge devices with the input impedance of the second device forming part of the load of the first device, and a low-resistance high-reactance connecting the grid of the second device to ground.
- 24 17. A wave repeating system of the type employing a pair of three-electrode electric discharge devices with the load of the first device between the cathode and the negative terminal of the anode supply, a conductive path for maintaining the grid of the second device at a predetermined static potential with respect to ground to limit the normal anode current of said second device while allowing said second device to operate with positive grid swing without causing distortion.
- 25 18. A wave repeating system comprising a pair of electric discharge devices each having cathode, anode and control electrodes, a signal input coil having one end connected only to the grid of the first device, the other end of said coil being directly connected to the cathode of the second device, and a high reactance direct current path connecting both said cathodes.
- 26 19. A wave repeating system comprising a pair of electric discharge devices each having anode, cathode and control electrodes, a direct current connection from the cathode of the first device to the grid of the second device, and a high-reactance impedance of relatively low ohmic resistance for maintaining the grid of the second device in the neighborhood of ground potential when no signals are being repeated.
- 27 20. A wave repeating system comprising a pair of electric discharge devices each having cathode, anode and control electrodes, a source of anode potential having its positive pole connected to the anode of the first device and its negative terminal connected to the cathode of the second device, a direct current connection from the cathode of the first device to the grid of the second device, and a high-reactance shunting the grid-cathode of the second device.
- 28 21. A wave repeating system comprising a pair of electric discharge devices each having cathode, anode and control electrodes, means for impressing signal variations to be repeated across the grid of the first device and the cathode of the second device, a metallic connection between the cathode of the first device and the grid of the second device to maintain the same phase relation between the signal variations impressed on both said grids, and an inductive reactance of low ohmic resistance connecting the cathode of the first device and the grid of the second device to the negative terminal of the anode supply.
- 29 22. In a transmission system of the type employing two sets of electron discharge elements each set comprising a cathode, anode and control electrode, a direct connection between the cathode of the first set and the control electrode of the second, means for limiting the normal anode current of the second set when no signals are being transmitted, said means consisting of a direct current path between the grid and cathode of the second set, an anode potential supply, input means for impressing signal variations on the control electrode of the first set, said input means making a direct current path between the last mentioned control electrode and a negative pole of the said anode potential supply.
- 30 23. A combination according to claim 22 in which said means for limiting the normal anode current comprises a resistance.
- 31 24. A combination according to claim 22 in which said means for limiting the normal anode current comprises a reactance.
- 32 25. A combination according to claim 22 in which the said negative pole of the anode supply is substantially at ground potential with respect to the signals to be transmitted.
- 33 26. A combination according to claim 22 in which the said cathode of the second set of elements is substantially at ground potential with respect to the signals to be transmitted.
- 34 27. In a transmission system of the type employing two sets of electron discharge elements each set comprising a cathode, anode, and control electrode, a direct connection between the

5 cathode of the first set and the control electrode of the second, means for limiting the normal anode current of the second set when no signals are being transmitted, said means consisting of a direct current path between the grid and cathode of the second set, an input circuit arrangement for impressing signal variations between the control electrode of the first set and the cathode of the second set, the variations in potential being 10 repeated across the control electrode and cathode of the second set approximately in phase with the said impressed signal.

10 28. In an electrical system, a first discharge valve; a second discharge valve, said valves having cathode, anode, and control electrodes; a source of energy; a direct conductive coupling connection from the cathode of said first valve to the control electrode of said second valve; means including circuit connections for connecting the 15 anode circuits of said valves in parallel across said source; and a choke coil inserted in the cathode lead of said first valve.

20 29. In an electrical system, a first thermionic valve; a second thermionic valve, said valves having cathode grid and anode electrodes; a source of anode potential; a direct conductive coupling connection from the cathode of said

first valve to the grid of said second valve; means including circuit connections for connecting the anode circuits of said valves in parallel across said source; and a resistance and a choke coil in series inserted in the cathode lead of 5 said first valve.

30. In an electric system, a first thermionic valve; a second thermionic valve, said valves having cathode grid and anode electrodes; a source of anode potential supply; a direct conductive coupling connection from the cathode of said first valve to the grid of said second valve; means including circuit connections for connecting the anode of circuits of said valves in parallel across said source; impedance means inserted in 10 the cathode leads of said valves comprising a choke coil in the cathode lead of said first valve for maintaining predetermined operating potentials of said electrodes and for producing coupling potential for said second valve.

15 31. In a system as described in claim 30, at least one further direct current circuit extending from the positive pole of said source over the cathode of said second valve, to the negative pole of said source.
